FREQUENCY MULTIPLIER

John Evans, Riverside, N. J., assignor, by mesne assignments, to Radio Corporation of America, New York, N. Y., a corporation of Delaware

Application November 30, 1934, Serial No. 755,392

8 Claims. (Cl. 250—36)

This invention relates to frequency multipliers and more particularly to a device in which frequency multiplication is obtained by suitable control of an electron beam in a cathode ray tube whereby a fundamental frequency impressed upon the deflecting circuits of such a tube may be multiplied to any desired frequency, harmonic or otherwise.

5 My invention has particular utility in ultra high frequency work. It has been found very difficult to economically obtain satisfactory frequency stabilization of ultra high frequencies. My solution of the problem enables one to use a crystal-controlled oscillator or any other oscillator of a fundamental frequency which can be accurately regulated and then to develop oscillations of any desired harmonic frequency under control of the fundamental frequency. The apparatus for accomplishing this result is so characterized that the fundamental frequency 10 may be multiplied many fold. The desired factor of multiplication is obtained by suitable design of one of the electrodes in a cathode ray tube. For a given tube this factor remains invariable, although, according to one modification of my invention presently to be described, a choice between several factors may be had.

20 In carrying out my invention I have chosen to utilize a cathode ray tube because it provides a dependable means for multiplying the frequency 30 of any desired fundamental source without resort to apparatus having any movable mass. My application of the cathode ray tube, therefore, provides further evidence of the many advantageous uses to which such a device may be put.

35 As is well known, energy can be so applied to the deflection of a focused beam of electrons as to produce a motion which is substantially devoid of inertia.

40 It is among the objects of my invention to provide a frequency multiplier of the type hereinabove suggested in which any desired factor of multiplication may be obtained.

45 It is another object of my invention to provide a frequency multiplier in which currents of considerable amplitude and at ultra high frequency may be generated.

50 Still another object of my invention is to provide suitable apparatus for stabilizing an ultra high frequency current.

55 The foregoing and other objects and advantages of my invention will be more clearly understood upon reference to the following detailed description when read in connection with the accompanying drawing in which

Figure 1 shows diagrammatically the circuit arrangements and electrode arrangements for a cathode ray tube as used in my invention, and

Fig. 2 is a plan view of a modified form of one of the electrodes such as may be used in the 5 cathode ray tube otherwise shown in Fig. 1.

Referring now to Fig. 1, I show a specially constructed cathode ray tube 1, the envelope of which contains a usual cathode 3 having, if desired, a separate heater element 5, a beam focusing anode 7, an accelerating anode 9, and further accelerating electrodes 11, 13 and 15. Beam deflecting means may be provided in the form of electrostatic plates 17 and 19 for horizontal and vertical deflection respectively. In place of the 10 electrostatic plates, magnetic deflecting coils (not shown) may be provided, if desired. In either case, the deflecting elements are included in circuits from a single-phase or polyphase source of energy. If a single-phase source only is available, as shown at 21, then a 90° phase shifting device 23 may be provided in one of the circuits 15 which includes the deflecting means 11. One of the electrostatic plates 17 and also one of the plates 19 may, if desired, be grounded as at 25. 20 In order to control the amplitude of beam deflection I may provide a rheostat 27 having a movable tap 29 which is also grounded.

The action of the cathode ray tube, insofar as it is controlled by the electrodes thus far described, is such as to project a beam of electrons 30 rotatably against the target electrode 11. Some of the electrons in the stream are, therefore, permitted to accelerate through the apertures 31 and to continue their course in the direction 35 of the electrode 13. The electron beam is so sharply focused that substantially the full force of the electron gun will be directed at one time through a single hole 31 and next against the wall of the target 11 adjacent two of the holes. 40 The beam is, therefore, intermittently interrupted. The electrons emerge intermittently on the other side of the target 11 and are further directed and controlled in their course back and forth in the cylindrical zone bounded by the electrodes 11 and 13 at the two ends thereof and 45 a circumferential electrode 15 which is preferably located mid-way between the other two. A source of direct current 33 is provided in connection with the electrode 15 so as to render 50 the latter more positive than either of the electrodes 11 or 13.

55 Connections from the electrodes 11 and 13 are made to opposite terminals both of an inductance 35 and of a shunt connected variable capacitor

37. A mid-tap on the inductance 35 connects with the negative side of the source 33. Suitable potentials are applied between the remaining electrodes of the cathode ray tube as indicated 5 at 39, 41 and 43, respectively.

It has been found desirable to provide still further means for directing the course of the electrons after they have emerged from the ori-fices 34 so that their paths shall be substantially 10 parallel with the axis of the electron gun up until they are attracted to the ring-shaped anode 45. Such a means may comprise a magnetic coil 45 so surrounding the enlarged cylindrical portion 15 of the cathode ray tube 1 as to produce a magnetic field having its lines of force substantially parallel 20 to the tube axis. Any suitable energizing source such as the battery 47 may be provided for the coil 45. The velocity of the electrons is made such that the secondary electrons emitted by 25 the impact of the primary electrons progress back and forth repeatedly between the electrodes 11 and 13, gradually releasing more and more electrons from these emissive elements until the beam itself attains considerable magnitude compared with that of the beam projected by the 30 electron gun. It is, therefore, possible under these circumstances to control the generation of oscillations of ultra high frequency in an output circuit which includes the shunt connected impedance 35 and capacitor 37, this result being obtained by the employment of comparatively low power applied to the electron gun and to the deflecting circuits. The increase in power output 35 is derived largely from the source 33 which has no effect upon the action of the electron beam prior to its emergence through the apertures 31.

According to a modification of my invention as shown in Fig. 2, the target 11a may be provided with apertures of different shapes and sizes so 40 that different factors of multiplication may be obtained by merely controlling the radius of curvature of the electron beam as it is intercepted by this target. Thus suitable adjustment of the rheostat 27—29 enables one to vary the deflecting 45 force as applied both to the horizontal and to the vertical deflecting elements simultaneously. The circular path of the electron beam is, therefore, maintained; but in one case if its radius is as shown at r , a low factor of multiplication will be 50 obtained because only the apertures 31a extend to within this radius. If the deflecting force is increased to an intermediate value, then the path of the electron beam may have a radius r' so as to comprehend both the apertures 31a and additional apertures 31b. With the employment of a 55 maximum deflecting force, the radius of the electron beam may be increased to r'' thereby comprehending all of the apertures in the target 11a including apertures 31a, 31b and 31c. Thus different factors of multiplication may be obtained at 60 will.

It is apparent that upon the employment of any fundamental frequency a multiplication of that frequency may be obtained, the factor of 65 multiplication being determined solely by the number of apertures through which the electron beam is successively projected while being deflected through a 360° arc as traced upon the target 11. The frequency of rotation about this 70 arc is determined by the frequency of the source 21. Since any well known means of frequency stabilization may be applied to the source 21, it is apparent that such stabilization may also be extended to the multiplied frequency as obtained 75 in the output circuit for the cathode ray tube 1.

Utilization of the multiplied frequency may be had by suitable connections or coupling with the output circuit in any well known manner.

Although I have disclosed herein certain specific means for accomplishing the objects of my invention, these are given merely by way of example and are not to be construed as limitations to the scope of my invention. It will be apparent to those skilled in the art that my invention is not thus limited, but many modifications may be 10 made without departing from the scope of my invention as set forth in the appended claims.

I claim as my invention

1. In a device of the class described, an electron discharge tube, an apertured electrode separating two portions of said tube and including therein a plurality of equally spaced apertures uniformly disposed with respect to the center of said electrode, means including other electrodes in one portion of said tube for projecting a stream of electrons successively through different apertures in the first said electrode and into the other portion of said tube, additional electrodes in the last said portion of said tube, a resonant output circuit connected between one of the last 25 said electrodes and the apertured electrode for producing secondary emission under control of the stream of electrons first mentioned, whereby oscillations of high frequency and high power are set up and a source of polarizing potential 30 connected between another of said additional electrodes and a point intermediate the ends of said resonant output circuit.

2. Apparatus in accordance with claim 1 further characterized in that the first mentioned 35 electrode and one other electrode of the tube portion into which the electron stream is last projected are made emissive and another of said additional electrodes is a ring shaped anode interposed between said emissive electrodes, and 40 charged positively with respect to said emissive electrodes.

3. In an oscillation generator, a cathode ray tube having heater, cathode, and focusing electrodes of the electron gun type and having both 45 horizontal and vertical beam deflecting means, and a plurality of additional electrodes for producing an accelerating electronic emission beyond the zone of beam deflection, one of said additional electrodes having a plurality of apertures 50 concentrically spaced and increasing in number with increasing distances from the center of said electrode and being so related as to alternately intercept and pass electrons therethrough, means for producing electron multiplication between said apertured electrode and one of said 55 additional electrodes by secondary emission from each of the last said electrodes, an output circuit connected between said apertured electrode and one of said additional electrodes and resonant to the frequency of interception and passage of said electrons, and means for biasing the electrodes connected to said output circuit with respect to one of said additional electrodes positioned intermediate said two connected electrodes comprising a connection intermediate the ends of said output circuit and a source of potential connected between said connection and said one additional electrode.

4. In a frequency multiplier, an electron discharge tube having a cathode, a beam focusing electrode, horizontal and vertical beam deflecting means and a plurality of accelerating electrodes, one of the last said electrodes having apertures therein through different ones of which 75

an electron beam may be successively projected, a source of single phase alternating current, means for splitting said alternating current into at least two phases and acting upon the beam deflecting means for timing recurrent rotative deflections of the electron beam, means including said apertured electrode for producing secondary emission and multiplication of electrons in that portion of the beam beyond the apertured electrode, a polarized output circuit for said discharge tube connected to said means for producing secondary emission and characterized in that an alternating current may be produced therein at a frequency determined by the rate of interception of said electron beam by different portions of said apertured electrode between the apertures thereof, and further characterized in that said output circuit includes an inductance having a center-tap and a capacitance shunting said inductance, the center-tap being connected through a source of direct current potential to a ring-shaped anode, and the terminals of the inductance being connected respectively with different ones of the electrodes comprised in the means for producing secondary emission, whereby said output circuit is made resonant to the frequency of the passage of electrons through said apertured electrode.

5. A frequency multiplier in accordance with claim 4 further characterized in that there is provided a source of magnetic flux the lines of which co-iningle with said electron beam beyond said apertured electrode and have a trend parallel to the direction of said beam.

6. A frequency multiplier in accordance with claim 4 further characterized in that said output circuit is tuned to a frequency harmonically related to the frequency of said alternating current that acts upon the beam deflecting means.

7. In an oscillation generator and frequency multiplier, a source of two-phase current of a fundamental frequency, a target having apertures disposed in circular formation, the number of apertures being determined by the multiplication factor to be applied to the fundamental frequency, a cathode ray tube having said target

as one of its anodes, and having other electrodes serving as an electron gun, beam deflecting means for so controlling an electron discharge from said gun as to direct the beam successively through different ones of the apertures in said target, 5 connections from said source of two-phase current to said beam deflecting means for controlling said beam, and secondary emission means including additional electrodes on the opposite side of the target with respect to said electron gun and said apertured target and including a tuned output circuit interconnecting the additional electrodes and the target for producing an amplified alternating current at the desired 10 multiple frequency, and comprising a center tapped inductor and a capacitor and a source of biasing potential connected between said center tap and a ring shape electrode intermediate said secondary emission means.

8. In an oscillation generator, an electron discharge device having a cathode, a beam-focusing anode, and an accelerating anode, horizontal and vertical beam deflecting means for said device, means including a source of alternating current and a phase-shifting device for so energizing said deflecting means as to effect a rotary movement of the electron beam within said discharge device, a shield having a plurality of holes arranged in the path of said electron beam, means for accelerating electrons after they are 30 shot through said shield, said means comprising additional electrodes in said device, and means including a source of energy and an output circuit comprising a center-tapped inductor and a capacity connected with said shield and with said additional electrodes for producing secondary emission from said shield said source of energy being connected between said center tap and a ring shape electrode positioned between said secondary emission electrode and for generating 40 in said output circuit oscillations of a frequency which is determined by the speed of rotation of the electron beam and by the number of holes in said shield.

JOHN EVANS. 45
